GAME NET END MEMBER

Joie L. Stapleton, Lawrence, Kans.

Application May 19, 1950, Serial No. 162,954

2 Claims. (Cl. 273—29)

1

This invention relates to the field of athletic equipment and has to do primarily with games such as Ping-pong, tennis and badminton, the most important object being to provide a combination tensioning device and releasable supporting means for game nets that is also adjustable for varying the height of such net.

One of the principal objects of the present invention is to provide a pair of end pieces for game nets, each of which is extensible and adapted for positioning within suitable brackets that are in turn mounted on a support whereby the entire net and its end pieces may be quickly and easily removed and/or positioned ready for use by merely retracting the end pieces.

Another important object of the present invention is to provide a tensioning device for game nets that is mounted as a unit upon one of the aforesaid extensible end pieces and including a windlass for receiving a pair of spaced-apart cables forming a part of the net itself.

A further object of this invention is to provide a game net having a pair of extensible end pieces, each of which is provided with a pair of opposed pins, one of the pins being reciprocably mounted within the end piece and biased outwardly therefrom and the other pin having a plurality of corrugations for engaging a bracket whereby the height of the net can be selectively chosen to suit the desires of the players.

Other objects, including details of construction, will be made clear or become apparent as the following specification progresses, reference being had to the accompanying drawing, wherein:

Figure 1 is a top plan view of a combination game net bracket and stretching apparatus made in accordance with my present invention.

Fig. 2 is a side elevational view thereof.

Fig. 3 is an enlarged, detailed, fragmentary, cross-sectional view taken on line III—III of Fig. 2; and

Fig. 4 is a transverse, cross-sectional view taken on line IV—IV of Fig. 2 looking in the direction of the arrows.

A net, for the most part of conventional character and commonly employed in the playing of such games as tennis, badminton, Ping-pong and the like, is clearly illustrated in Fig. 2 of the drawing and broadly designated by the numeral 10.

Net 10 includes a pair of spaced-apart, substantially parallel, longitudinally extending cables 12 and 14 joined adjacent the ends thereof by a pair of transverse cords 16 and 18. The cables 12 and 14 and the cords 16 and 18 are in

2

turn all interconnected by a plurality of cords 20, arranged in a crisscross pattern.

Net 10 is conventionally stretched between a pair of upright supports 22 and 24 that may constitute posts or other rigid constructions and, for the purposes of this invention, each of the supports 22 and 24 is provided with a pair of opposed, horizontally extending brackets 26 having eyelets 28 on the outermost free ends thereof. 10 Any suitable means may be employed for attaching the brackets 26 either rigidly or permanently to the supports 22 and 24. Brackets 26 receive, through the medium of the loops 28 thereof, a pair of opposed end pieces 30 and 32 for the net 15 10. End pieces 30 and 32 preferably include an elongated tubular body 34 having pins 36 and 38 extending outwardly from the uppermost and lowermost ends thereof. Tubular body 34 has a perforated end wall 40 for slidably receiving pin 20 38, there being an out-turned flange 42 on the innermost end of rod 38 slidable within body 34. Flange 42 receives one end of a coil spring 44 within body 34, the opposite end of the spring 44 bearing against a transverse pin 46 in body 34 spaced from end wall 40 of the latter. Spring 44 accordingly yieldably biases the pin 38 outwardly with respect to the body 34 and outward movement of pin 38 is limited by a stop 48 in body 34 on that side of flange 42 opposite to spring 44. As illustrated, the pin 38 passes loosely through the lowermost eyelet 28, while the pin 36 extends upwardly through the corresponding uppermost eyelet 28.

Vertical movement of the entire end piece 30 or 32 as the case may be, with respect to the corresponding supports 22 and 24 respectively, is limited by a plurality of kinks or corrugations 50 formed in the pins 36 throughout the length thereof. The length of the pins 36 is sufficient to prevent release of the end pieces 30 and 32 in the event the net 10 is accidentally slackened. In other words, the ends 40 of the end pieces 30 and 32, will move against the lowermost loops 28 before pins 36 slip from their normal position within the uppermost loops 28.

45 The tubular body 34 for the end piece 32, is provided with a pair of opposed laterally extending eyelets 52 and it is within these eyelets 52 that one end of the cables 12 and 14 are permanently tied. The cables 12 and 14 at that end thereof adjacent the cross-cord 16, are threaded through pulleys 54 and 56 respectively rotatably mounted in bifurcated brackets 58 carried by the tubular portion 34 of end piece 30.

55 A windlass includes a drum 60, rotatably car-

ried by a bifurcated bracket 62 on end piece 30 between brackets 58. That end of the cables 12 and 14 opposite to eyelets 52 is secured directly to the drum 60 and wound thereabout as illustrated in Figs. 1 and 4. A crank 64 on drum 60, serves as a means for rotating the latter and any suitable ratchet-pawl means or other mechanism (not shown) may be employed to hold the crank 64 and the drum 60 against counter-rotation after the net 10 has been suitably tensioned or stretched between end pieces 30 and 32.

While the operation is quite apparent, it is important to point out that the entire tensioning or stretching means for the net 10, is carried by the end piece 30 as a unit and is movable therewith with respect to the support 22. It is notable further that the tensioning assembly hereof cooperates with the pins 36 in holding the entire net and its supports 30 and 32 against vertical movement within the eyelets 28 of brackets 26. As long as the net 10 is tightly stretched between the end pieces 30 and 32, the pins 36 and 38 will bear tightly against the eyelets 28 at the bight thereof and because of the corrugations 50, vertical movement of the pins 36 is prevented.

Removal of the entire assembly from the position illustrated in Figs. 1 and 2, is accomplished by merely rotating the drum 60 in a counter-direction, thereby releasing the tension on net 10. The two end pieces 30 and 32 may thereupon be easily and quickly removed from the brackets 26 by merely moving pins 38 inwardly within tubular bodies 34 against the action of the corresponding springs 44. Such retraction of the pins 38 decreases the overall length of the end pieces 30 and 32 to that less than the distance between brackets 26 and permits removal of net 10 and end pieces 30 and 32 as well as the tensioning apparatus including drum 60 from the supports 22 and 24. By virtue of the provision of a plurality of corrugations 50 on the pins 36, the height of the net 10 can be varied within close proportions and it is obvious further that the entire structure can be utilized for a number of games where the net 10 must be of differing heights by the mere provision of a plurality of brackets 26 upon supporting means 22 and 24.

Many other advantages will emanate from use of the net assembly hereof and those that

fairly come within the spirit of this invention as defined by the scope of the appended claims, are contemplated hereby.

Having thus described the invention, what is claimed as new and desired to be secured by Letters Patent is:

1. As an article of manufacture, an end member for game nets comprising an elongated tube having means thereon adapted to receive one end of a game net; and a bracket-receiving pin extending from each end of said tube, one pin projecting into the tube and being biased outwardly therefrom, the other pin having bracket-engaging corrugations thereon for releasably holding the same against movement relative to its bracket.

2. In a game net assembly, a pair of spaced posts, each having a pair of spaced brackets; an upright end member for each post, each member including an elongated element having a pin extending from each end thereof; the brackets each being provided with an eye for receiving a corresponding pin; a game net joining the elements; means mounting one pin of each element for reciprocation on the longitudinal axis of the element; and means carried by each element for yieldably holding the reciprocable pin thereof biased outwardly whereby to render the member releasable from the brackets upon retraction of the reciprocable pins, the other pin of each element having bracket engaging corrugations thereon for releasably holding the same against movement relative to its brackets.

JOIE L. STAPLETON.
